INVENTOR.

BY *Edwin T. Carkas*
ATTORNEY.

UNITED STATES PATENT OFFICE.

FRANK O. ACKERS, OF COLUMBUS, OHIO, ASSIGNOR TO THE SAFETY WIRE GAS GLOBE COMPANY, OF COLUMBUS, OHIO.

TOOTH-BRUSH HOLDER.

1,291,349.

Specification of Letters Patent.

Patented Jan. 14, 1919.

Application filed June 22, 1917. Serial No. 176,364.

To all whom it may concern:

Be it known that I, FRANK O. ACKERS, a citizen of the United States of America, residing at Columbus, in the county of Franklin and State of Ohio, have invented certain new and useful Improvements in Tooth-Brush Holders, of which the following is a specification.

My invention relates to tooth brush holders and contemplates the provision of a simple and unitary shelf structure designed to support a plurality of tooth brushes and the supplies accessory thereto. My object is to provide a formation that may be stamped out of one piece of sheet metal and yet may be so reinforced and formed as to insure rigidity and long-life.

One of the problems involved is the cost of manufacturing, this being particularly true in view of the high cost of materials. Another problem of even greater importance is that of sanitation. The holder must be of sufficient strength and properly reinforced at necessary points; and yet it must be free from dirt-collecting crevices, particularly at points adjacent the bristles of the tooth brush.

The preferred embodiment of my invention is shown in the accompanying drawings wherein similar characters of reference designate corresponding parts.

Figure 1 is a perspective view of the invented holder, illustrating the capabilities thereof.

Fig. 2 is a transverse section of the structure shown in Fig. 1.

In the drawings, the holder is shown stamped from sheet steel and it will appear that it comprises a back 1 and a key slot eyelet 3 by means of which it may be attached to a wall or other surface. Stamped out of the center of this back plate 1 is a channel member 4 which is designed to receive and support a tube of tooth paste.

Integrally formed upon the back plate and extending forward at right angles thereto is a base plate 5 having a stamped up reinforcing rib 6 and a turned down outer edge 7. In addition, the back plate is provided with triangular wings 8 and these wings preferably extend below the base plate to form side flanges 9.

The front edge of the base plate 5 and its reinforced lip 7 are cut away to form key-hole indentations 10 and these indentations 55 are each adapted to receive and support a tooth brush in the manner indicated in the drawings.

The forward edges of the triangular wings 8 are notched as are 11 and the downwardly turned lip 7 is provided at each end with a reduced extension 12. Each extension 12 fits in the notched end of each wing 8 and is folded around back and against the outer side of each wing. 65

The structure is, therefore, not only formed of one piece; but it is rigidly reinforced at a number of points and the main parts are firmly locked together by the reduced extension 12. Obviously, enough 70 space will be provided for tooth brushes and toilet articles connected therewith, although the device is comparatively small and compact.

Having thus described my invention, what 75 I claim is:

1. A tooth brush holder comprising a main shelf, a back, side wings and a supplemental trough shaped shelf on said back, said supplemental shelf being centrally located and 80 of such length relative to said main shelf that there result pocket-like spaces at either end of said main shelf between said supplemental shelf and said wings.

2. A tooth brush holder comprising a main 85 shelf, a back, side wings and a supplemental trough shaped shelf on said back, said supplemental shelf being centrally located and of such length relative to said main shelf that there result pocket-like spaces at either 90 end of said main shelf between said supplemental shelf and said wings said main shelf having cut-out places in the forward edge for the reception of tooth brushes.

3. A tooth brush holder comprising a back 95 plate, side wings with notches in their forward edges, a base plate, a depending lip on the forward edge of this base plate, a reduced extension on said lip designed to fit in such notches and fold over against the sides of 100 said wings.

In testimony whereof I hereby affix my signature.

FRANK O. ACKERS.
